MODULATOR

Roberto M. Fano, Boston, Mass., assignor, by
mesne assignments, to the United States of
America as represented by the Secretary of the
Navy

Application November 29, 1945, Serial No. 631,755

8 Claims. (Cl. 250—36)

1

This invention relates to apparatus for amplitude modulating radio frequency energy and more particularly to apparatus for amplitude modulating such energy by mechanical means.

It is sometimes necessary to generate a standard amplitude modulated signal whose percentage modulation is independent of frequency. The conventional way of varying the amplitude of a microwave signal is to introduce a piece of resistance card into the transmission line and periodically vary the amount of insertion. This proves to be unsatisfactory because the attenuation introduced by the card depends on the impedance of the load which in turn may vary with frequency.

It is an object of this invention to provide apparatus for amplitude modulating a microwave signal.

It is another object of this invention to provide apparatus for amplitude modulating a microwave signal by mechanical means.

It is a further object of this invention to provide apparatus for amplitude modulating a microwave signal such that the percentage modulation remains constant over a broad band of frequencies.

Other and further objects will appear during the course of the following description taken with the accompanying drawings in which:

Fig. 1 shows a sectional view of one embodiment of this invention;

Fig. 2 is a partially cut away and enlarged view of a portion of the embodiment of Fig. 1;

Fig. 3 is a sectional view along the line III—III in Fig. 2;

Fig. 4 is an equivalent circuit diagram in constant voltage form of the embodiment of Fig. 1; and

Fig. 5 is an equivalent circuit diagram in constant current form of the embodiment of Fig. 1.

The modulator consists, mainly, of a continuously variable coupler joining two waveguides (the word waveguide is here and hereinafter used in a broad sense and includes any type of transmission line). One guide is fed by an unmodulated source and is terminated into a load. Part of the power is coupled into the second guide by means of the variable coupler. If the power coupled out of the first guide is small compared to the total power delivered by the source (1% or less), the amplitude of the signal in the second guide is very nearly independent of frequency. The coupling can be varied periodically to give the desired form and amount of amplitude modulation.

2

The embodiment shown in Fig. 1 comprises a continuously variable coupling between two coaxial transmission lines 10 and 11. A source of radio frequency energy 12 is connected to a Poly-iron matched load 13 by coaxial line 10 whose center conductor consists of a fixed section 10_b and a section 10_c which is rotatable with respect to outer conductor 10_a by means of motor 15 through gears 16_a and 16_b. The rotatable section 10_c is flattened on two opposing sides in a taper fashion as shown in Fig. 2 and Fig. 3, and a rotating joint 17 effectively joins center conductors 10_b and 10_c. This rotating joint comprises center conductor 10_b milled out to form a recessed pin 18 as shown. The adjacent end of center conductor 10_c is shaped to receive a carbon bushing 19 which is adapted to enclose pin 18. Annular groove or channel 20 is thus formed which, being one-half wavelength long, reflects the short circuit produced by terminating wall 21 at gap 22 between center conductors 10_b and 10_c. Carbon bushing 19 serves as a bearing and also maintains proper alignment of center conductor 10_c at the rotating joint while ball bearing 23 provides support at its other end. Joining coaxial line 10 at right angles is another coaxial line 11 whose center conductor extends through slot 24 in outer conductor 10_a and into coaxial line 10 to form probe 14. The position of probe 14 is adjustable by moving coaxial line 11 along coaxial line 10 in an axial direction.

Coaxial line 10 is fed by a source of unmodulated radio frequency energy, matched load 13 furnishing a non-critical termination to absorb the energy and prevent reflections over the necessary frequency range. Part of the energy is coupled into coaxial line 11 by means of adjustable probe 14, the amount depending on the angular position of center conductor 10_c for any given probe position.

The coupling can then be varied periodically by rotating the center conductor to give an amplitude modulated output having a waveform similar to a sine wave. The maximum coupling or the energy level is fixed substantially by the amount of insertion of probe 14 while the minimum coupling or the percentage modulation can be adjusted by moving probe 14 along coaxial line 10 in an axial direction. Thus the amount of amplitude modulation can be adjusted to the desired value.

Since the power coupled out by probe 14 is small compared to the power dissipated in termination 13, the modulation of the output signal is very nearly independent of the load imped-

ance and the frequency. To demonstrate this, consider Fig. 4, the constant voltage equivalent circuit of the embodiment of Fig. 1, in which E_s is the voltage of source 12, Z_s is the internal impedance of source 12, Z is the impedance of matched termination 13, Y_c is the admittance of the coupling between probe 14 and center conductor 10c, and Z_L is the impedance of the external load.

The probe coupling can be represented, to a first approximation, by the capacitance between probe 14 and center conductor 10c. Since the coupling impedance

$$\frac{1}{Y_c}$$

of the probe is much larger than both

$$\frac{ZZ_s}{Z+Z_s}$$

(the impedance of the main line as seen by the probe) and Z_L , the modulator circuit is equivalent to the circuit diagram shown in Fig. 5.

The voltage across the load Z_L is, therefore, proportional to the coupling susceptance B_c . Then if the susceptance B_c , at any given frequency, is a function of time, $B_c = B_0 [1+f(t)]$ the load voltage is amplitude modulated, since

$$E_L = jE \cdot \frac{Z}{Z+Z_s} B_0 Z_L [1+f(t)]$$

The modulation envelope, $1+f(t)$, depends only on the time variation of the coupling susceptance, provided, of course, the simplifying assumptions as to the magnitude of

$$\frac{1}{Y_c}$$

are satisfied. Moreover, if the susceptance B_c were controlled only by the capacitance C_c between probe 14 and center conductor 10c, then

$$B_c = \omega C_c = \omega C_0 [1+f(t)]$$

and the modulation envelope would be independent of frequency. Although susceptance B_c is controlled by other parameters besides C_c , the percentage modulation will in general remain substantially constant over a wide frequency band.

The modulation frequency is equal to twice the number of revolutions per second of center conductor 10c and can be adjusted to the desired value by varying the speed of driving motor 15.

The term Polyiron indicates a material composed of powdered iron mixed with a phenolic binder.

This invention is only to be limited by the appended claims.

What is claimed is:

1. Apparatus for amplitude modulating radio frequency energy by means of a continuously variable coupling comprising, a coaxial transmission line having a rotatable center conductor whose diameter varies along its axial direction, said rotatable conductor being flattened to form two opposed sides a second coaxial transmission line coupled to said first coaxial line by means of an extension of the center conductor of said second coaxial line and forming the output connection, means for rotating said rotatable center conductor to vary the coupling between the two said coaxial lines, whereby the radio frequency energy in said first coaxial line is amplitude modulated as received by said second coaxial line.

2. Apparatus for amplitude modulating radio

frequency energy comprising, a coaxial transmission line having one end adapted for connection to a source of radio frequency energy and having a load on the other end to absorb energy from said source, a portion of the inner conductor of said coaxial line being rotatable with respect to the remainder of said inner conductor, opposing sides of said rotatable portion being flattened in a taper fashion to provide recesses thereon, a second coaxial transmission line forming the output connection and coupled to said first coaxial line by means of an extension of the center conductor of said second coaxial line to form a probe adjacent said recesses on said rotatable center conductor, and means for rotating said rotatable center conductor to vary the coupling periodically between said probe and said rotatable center conductor, whereby the radio frequency energy from said source is amplitude modulated as received by said second coaxial line.

3. Apparatus for amplitude modulating the output of a microwave generator comprising, a coaxial transmission line having one end adapted for connection to said generator and having a load on the other end to absorb energy from said generator, a portion of the inner conductor of said coaxial line adjacent said load being rotatable with respect to the remainder of said inner conductor, a rotating joint which effectively joins the fixed portion of said inner conductor and said rotatable portion as well as providing an end bearing, opposing sides of said rotatable portion being flattened in a taper fashion to provide recesses thereon, a slot in the outer conductor of said first coaxial line, a second coaxial transmission line connected at right angles to said first coaxial line at said slot to form the output connection and being adjustable along said first coaxial line in an axial direction, an extension of the center conductor of said second coaxial line through said slot to form an adjustable probe adjacent said recesses on said rotatable center conductor, and means for rotating said rotatable center conductor to modulate the radio frequency energy amplitude from said generator as received in said second coaxial line.

4. Apparatus for amplitude modulating the radio frequency energy transmitted from one transmission line to a second transmission line comprising, a variable coupling device having an outer cylindrical conductor and an inner rotatable center conductor, said inner rotatable center conductor being tapered along its rotational axis and being formed to have opposed flat surfaces, means to couple said first and second transmission lines to said device, and means to rotate said rotatable center conductor to vary the amount of coupling between said transmission lines.

5. Apparatus for amplitude modulating the radio frequency energy transmitted from one transmission line to a second transmission line comprising, a variable coupling device having an outer cylindrical conductor and an inner rotatable center conductor, said inner rotatable conductor being tapered along its rotational axis and being formed to have opposed flat surfaces, means to couple said first and second transmission lines to said device, means to adjust the coupling of said second transmission line to said device, and means to rotate said rotatable center conductor to vary the amount of coupling periodically between said transmission lines.

6. Apparatus for amplitude modulating the

radio frequency energy transmitted from one transmission line to a second transmission line through a coupling device comprising, a variable coupling device having an outer cylindrical conductor and an inner rotatable center conductor, said inner conductor having opposed flat surfaces and being tapered along its rotational axis, means to couple said first and second transmission lines to said device, means to adjust the coupling to said second transmission line, means to rotate said rotatable center conductor to vary the coupling periodically between said transmission lines, and means to apply an electrical load to said inner rotatable conductor to absorb power from said first transmission line whereby the amplitude of energy in said second transmission line is substantially independent of frequency.

7. Apparatus for amplitude modulating radio frequency energy by means of a continuously variable coupling comprising, a coaxial transmission line having one end adapted for connection to a source of radio frequency energy and having a load on the other end to absorb energy from said source, a portion of the inner conductor of said coaxial line being rotatable with respect to the remainder of said inner conductor, said rotatable portion being tapered along its rotational axis and being flattened to form two opposed sides, a second coaxial transmission line forming an output connection and coupled to said first coaxial line by means of an extension of the center conductor of said second coaxial line to form a probe adjacent said rotatable center conductor, and means for rotating said rotatable center conductor to vary the 35

coupling periodically between said probe and said rotatable center conductor.

5 8. Apparatus for amplitude modulating radio frequency energy by means of a continuously variable coupling comprising, a coaxial transmission having a rotatable center conductor whose diameter varies along its axial direction, said rotatable conductor being flattened to form two opposed sides, a second coaxial transmission line coupled to said first coaxial line by means of an extension of the center conductor of said second coaxial line and forming the output connection, means to vary the coupling between said lines by adjusting the position of 10 said second coaxial line with respect to said variable diameter conductor along the axial direction of said first coaxial line, and means for rotating said rotatable center conductor to vary the coupling periodically between the two said 15 coaxial lines.
